NÉE MERTTENS, OF VIENNA, AUSTRIA-HUNGARY.

LACING-HOLDER.

1,068,241.

Specification of Letters Patent.

Patented July 22, 1913.

Application filed April 22, 1910. Serial No. 557,010.

To all whom it may concern:

Be it known that I, LIBOR HLUCHÝ, a subject of the King of Bohemia, and residing at Příbram, Bohemia, Empire of 5 Austria-Hungary, have invented certain new and useful Improvements in Lacing-Holders, of which the following is a specification.

The subject of my invention is an im- 10 proved lacing-holder, which is of extremely simple construction and can be most readily and yet firmly secured in position.

A practical embodiment of the invention is illustrated in the accompanying drawing, 15 in which—

Figure 1 is a side elevation, the lace being shown in section, Fig. 2 an end elevation, Fig. 3 a plan, and Fig. 4 a longitudinal section on the line I—I of Fig. 3. Fig. 5 is 20 a plan of a double eyed washer, and Fig. 5^a is a section through the same on the line II—II of Fig. 5. Fig. 6 is a sectional view showing the holder secured in position, and Fig. 7 is an underside view of Fig. 6.

25 The new holder consists of a frame or shell 1, which may be made of a strip of stamped sheet metal bent into rectangular shape. The ends 2, 3 are brought close together at the corner 4 of the shell and are 30 downwardly directed. The end 3, which is a prolongation of the side 5 of the shell, is considerably shorter than the end 2, which extends from the side 6. The extremities of the two ends 2 and 3 are pointed and one 35 or both ends may be inwardly bent. The sides 5 and 7 are provided with studs 8, which may be pressed or drawn out of the material. These studs serve as journals for a small pulley or roller 9, which has a 40 groove 10 to accommodate the lace 16.

11 represents a washer, consisting of a rectangular plate having two oblong, parallel openings 12, 13. To fasten the holder to the leather 14 or the like, a slit must be 45 pierced in the latter, of such size as to admit of the two ends 2, 3 of the shell being passed through. The washer 11 is placed with its opening or eye 12 over the ends 2, 3, which protrude through the leather. 50 Hereupon the ends 2, 3 are bent over and pressed through the aperture or eye 13, the shorter end 3 curving around the bridge 15 of the washer, and entering the leather, thus constituting a hook. The end 2 takes 55 over the end 3 and enters the leather below

the margin of the washer; it thus serves to lock the end 3 in place. This method of attaching the holder is exceedingly secure, and yet admits of the holder being removed without injury to the leather. Such a 60 holder, therefore, can be readily replaced by a new one, should it become damaged, since the slits to be made in the leather have merely to be large enough to admit the ends 2, 3, and can be employed again to receive 65 the ends of the new holder.

Having thus described my invention, I declare that what I claim as new and desire to secure by Letters Patent is—

1. A lacing-holder, comprising a frame 70 having pins projecting inwardly from its top and bottom walls, and a pulley rotatably mounted on the pins, said frame consisting of a metal strip bent to form a shell, one end of the strip constituting a prolongation 75 of one side-wall of the shell and being longer than the other strip-end, which extends at a right-angle from the shell-base, and lies throughout its entire length with its plane face closely against the plane face 80 of the first said strip-end, both strip-ends having sharp points so as to form fastening-means, substantially as described.

2. In combination, a piece of fabric, and 85 a lacing-holder, comprising a pulley, and a frame in which the latter is vertically mounted, consisting of a metal strip bent to form a shell, whose base rests on the face of the fabric, the ends of the strip lying closely together at the point of junction of 90 the base and one wall and passing immediately at such junction-point, and at right-angles to the base, through a common hole in the fabric, and jointly reentering the 95 back thereof below the shell, the strip-end which extends from the said wall being longer than the other strip-end, and lying tightly against the same and thus covering it and locking it in position, substantially 100 as described.

3. In combination, a piece of fabric, a lacing-holder, comprising a pulley, and a frame in which the latter is vertically mounted, consisting of a metal strip bent to form a shell, whose base rests on the face of the fabric, the ends of the strip lying closely together at the point of junction of 105 the base and one wall and passing immediately at such junction-point, and at right angles to the base, through a common hole 110

in the fabric; and a washer located at the back of the fabric and presenting two openings, which lie in the vertical plane of the longitudinal axis of the device and are separated by a straight bridge, the one opening being in alinement with the hole in the fabric and the other opening lying below the shell, the strip-ends passing jointly through the first washer-opening and bending around the said bridge, returning together through the second washer-opening and reëntering and gripping the fabric, that strip-end

which extends from the said shell-wall being longer than the other strip-end and lying tightly against the same, thus covering and locking it in position; substantially as described.

In testimony whereof I affix my signature in presence of two witnesses.

LIBOR HLUCHÝ.
